Mass., a corporation of Massachusetts

Application March 27, 1947, Serial No. 737,677

15 Claims. (Cl. 216—38)

1

This invention relates to a labeling machine and more particularly to label wiping mechanism for a labeling machine.

The invention has for an object to provide a novel and improved apparatus for pressing or wiping a label against a curved surface of a container and more specifically for wiping the extended portions of a label about the conical surface of the tapered neck of a bottle in a novel, efficient and practical manner.

With this general object in view, and such others as may hereinafter appear, the invention consists in the labeling machine and in the various structures, arrangements and combinations of parts hereinafter described and particularly defined in the claims at the end of this specification.

In the drawings illustrating the preferred embodiment of the invention, Fig. 1 is a plan view of a labeling machine embodying the present invention; Fig. 2 is a side elevation of the present label wiping mechanism; Fig. 3 is a detail view of operating levers as viewed from the right in Fig. 2, to be hereinafter referred to; Fig. 4 is a plan view of the present wiping mechanism shown in one position of operation; Fig. 5 is a front elevation of the mechanism shown in Fig. 1; Fig. 6 is a plan view similar to Fig. 4 showing the mechanism in a different position of operation; and Fig. 7 is a developed view of the label applied to the illustrated tapered neck bottle.

In general, the present invention contemplates a labeling machine having novel label wiping apparatus for wiping a label about the conical surface of the tapered neck of a bottle in a novel manner such as to provide a true rolling contact against the conical surface whereby to effect a uniform wiping pressure about the conical surface. In the illustrated embodiment of the invention the wiping member comprises a tapered roller or frustum of a cone arranged to engage the surface of the tapered neck of the bottle which has the general shape of a frustum of a cone, and provision is made for moving the roller through an arcuate or circular path in an inclined position about the vertical axis of the bottle with the extended center line or axis of the roller and the axis of the bottle having a common apex, the motion being equivalent to the rolling contact of two right cones or the frusta of cones having a common apex.

Referring now to the drawings, the invention is, for purposes of illustration, herein shown as embodied in a labeling machine of a known type

now upon the market and which is provided with an intermittently operated conveyer 10 arranged to support and move the containers 12 in uniformly spaced relation for presentation in operative position to successive of various labeling mechanisms disposed along the sides of the conveyer. Reference is made to the patent to C. S. Weeks, No. 1,425,351, dated August 8, 1922, as disclosing the general details of construction and mode of operation of such prior art labeling machines. Inasmuch as many portions of the labeling machine of themselves constitute no part of the present invention, it has been deemed sufficient to herein illustrate and describe only such portions as will enable the invention to be understood.

The illustrated container 12 comprises a tapered neck bottle to which a relatively narrow label 14 is supplied. Referring to Fig. 1, in the illustrated labeling machine, a bottle is first presented to an adhesive applying mechanism, indicated generally at 16, arranged to apply a film of adhesive 18 about one side of the tapered neck of the bottle. The adhesive applying mechanism 16 comprises a flexible glue pad 20 mounted on a yieldable linkage 22 carried by a reciprocating bar 24. In its retracted position, the pad 20 is presented flat in alignment with a vertically reciprocal transfer roller 25 arranged to be elevated into engagement with the glue pad to transfer a coating of adhesive thereto in the usual manner.

Thereafter, in the operation of the apparatus, when a bottle comes to rest in alignment with the applying mechanism, the pad 20 is advanced into engagement with the neck of the bottle, the linkage 22 being designed to permit the pad 20 to wrap itself about and follow the contour of the neck, as illustrated in dotted lines in Fig. 1, to apply the film of adhesive. The bottle is firmly held in an upright position on the conveyer 10 by a cooperating upper conveyer 26, as shown in Fig. 2, which is movable with the belt 10 and provided with pressure pads 28 engageable with the tops of the bottles to prevent lateral displacement thereof during their conveyance and during the various labeling operations. Upper guide rails 30, 32 may also be provided for engagement with the upper ends of the bottles, as shown.

The reciprocating bar 24 is arranged to be reciprocated in timed relation to the movement of the intermittently operated conveyer by any well-known mechanism such as that disclosed in the Weeks' patent above referred to, and, the

bottle thus provided with a film of adhesive 18 on one side of the tapered neck, is subsequently presented to a label applying station, indicated generally at 34, which includes a label box or magazine 36 mounted and operated in a manner for effecting the application of labels directly from the label magazine to the surface of the bottle. The label magazine is carried by a reciprocatory bar 33 arranged to move in a path transversely to the line of movement of the bottles. The labels 14 carried in the magazine 36 are arcuate in form, as illustrated in Fig. 7, and shaped to conform to a developed portion of the conical surface to which the label is to be applied.

Cooperating with the label magazine is a second reciprocatory adhesive applying device, indicated generally at 40, disposed on the opposite side of the conveyor 10. The adhesive applying device 40 comprises an open U-shaped frame 42 carried by a reciprocatory bar 44 and the frame is provided with laterally extended pads 46, 48 at the free ends of the legs of the U-shaped frame arranged to straddle the neck of the bottle when in its forwardly extended position. In its retracted position, the pads 46, 48 are disposed in alignment with a vertically reciprocal transfer roller 50 arranged to supply the pads with adhesive, and, in its forwardly extended or advanced position the pads are arranged to engage the ends of the label in the magazine while the latter is in engagement with the neck of the bottle.

Thus, in the operation of the machine, the magazine is advanced to present the foremost label in the magazine against the adhesive coated portion 18 of the tapered neck of the bottle and while thus disposed the adhesive applying pads 46, 48 are advanced and pressed against the laterally extended ends of the label to apply a film of adhesive to the same. Thereafter the magazine is retracted effecting withdrawal of the foremost label therefrom and upon retraction of the pads 46, 48 the label remains attached to the adhesive film 18 of the bottle and partly wrapped about the neck.

At the following station of operation, indicated generally at 52, the attached label is pressed or wiped against one side of the bottle by an arcuate and yieldingly mounted presser member 54 carried by a reciprocatory bar 56 to present the extended ends 100, 102 of the label substantially parallel to one another, the label taking the form of a U in plan, as illustrated in Fig. 1, preparatory to being wiped about the remaining side of the tapered neck of the bottle. The presser member 54 may and preferably will be shaped to conform to the tapered section of the bottle against which it is pressed.

At the two next succeeding stations of operation, indicated generally at 58, 60, the extended ends 100, 102 of the label are successively wiped into engagement with the remaining side of the bottle neck and preferably in overlapping relation as illustrated. Each wiping mechanism 58, 60 is similar in construction and mode of operation, each being provided with a conical wiping roller 62 mounted in an inclined position and which is caused to follow an arcuate path about the axis of the bottle and against the tapered neck thereof to perform the wiping operation. In operation, at the time the first extended end 100 of the label is being wiped by the first mechanism 58, the other extended end 102 of a preceding bottle is being wiped into overlapping relation with the first wiped extended end by the

simultaneously operated mechanism 60. Since both mechanisms 58, 60 are identical except that they are arranged for left and right hand operation, it is believed that a description of one will suffice for both.

As best shown in Figs. 4 and 5, the wiping roller 62 comprises a frustum of a cone having an apex 64 in common with the apex of a cone formed by extension of the surface 66 of the tapered neck of the bottle. The roller 62 is rotatably mounted on an arm 68 with the roller axis 70 in an inclined position and passing through the apex 64 when the roller is in contact with the bottle neck. The mechanism illustrated is arranged to move the inclined roller 62 about the vertical axis 72 in a manner such that the axis 70 of the roller is swung or revolved in a conical path with the fixed apex 64 as its center and the roller surface in engagement with the conical surface of the neck thus effecting a true rolling contact of the conical roller without slippage with relation to the conical surface of the tapered neck.

The conical wiping roller 62 is caused to follow a conical path about the neck of the bottle in an inclined position and with the roller at all times in contact with the surface of the neck of the bottle by compound or interconnected parallel linkages indicated generally at 74 and 76. As herein shown the roll carrying arm 63 comprises one arm of a right angle or 90° bell crank, the second arm 78 of which forms one parallel arm of the parallel linkage 74. The parallel linkage 74 includes a second parallel arm 80, a relatively fixed link 82 in which the parallel arms 78, 80 are pivoted at 84, 86 respectively, and a parallel link 88 connecting the ends of the arms 78, 80.

The parallel linkage 74 is interconnected with the second parallel linkage 76 carried by a rockingly mounted supporting arm 90 pivoted on a vertical shaft 92. As illustrated in Fig. 2 the vertical shaft 92 is journaled in a bracket 93 attached to the platen 95 of the machine frame. The second parallel linkage includes parallel arms 94, 96 pivotally mounted at relatively fixed pivots 104, 106 respectively in the supporting arm 90 and a parallel link 108 connecting the arms 94, 96. As clearly shown in Fig. 4, the parallel arm 94 of the linkage 76 is formed integrally with the parallel arm 88 of the linkage 74 and forming a right angle bell crank therewith having its pivot at 86, and, the parallel connecting link 108 of the linkage 76 is formed integrally with the relatively fixed parallel link 82 of the linkage 74 and likewise forming therewith a right angle bell crank also having its pivot at 86.

From the description thus far it will be seen that the compound parallel linkages 74, 76 are supported by the arm 90 on the shaft 92 and, as herein shown, provision is made for rocking the arm 90 to move the wiping roller 62 and its associated linkages into and out of operative relation to the bottle. As shown in Fig. 2, the arm 90 is arranged to be rocked by a cam 110 mounted fast on a cam shaft 112 forming a part of the labeling machine and through connections including a roller 114 carried by a lever 116 pivotally mounted at 118. The lever 116 is connected by a link 120 to one arm 122 of a two-armed lever fast on a rocker shaft 124, the second arm 126 being connected by a link 128 to the supporting arm 90.

Provision is made for rocking the compound linkages 74, 76 to effect the arcuate movement of

the roller 62 through connections including a bell crank pivotally carried by the supporting arm 90 at 130, one arm 132 of the bell crank being connected by a link 134 to the parallel arm 94, the second arm 136 of the bell crank being connected by a link 138 to one arm 140 of a two-armed lever rockingly mounted on the shaft 124. The second arm 142 of the two-armed lever is connected by a link 144 to a cam lever 146 carrying a roller 148 in cooperation with a cam 150 fast on the cam shaft 112. It will be observed that the rocker shaft 124 carries a second arm 152 fast thereon for effecting rocking movement of the simultaneously operated right hand wiping mechanism 60 and that the rockingly mounted arm 140 is provided with a second link 154 connected to operate the similar parallel linkages of said right hand wiping mechanism, the arrangement of the arms being shown in Fig. 3. Thus, both left and right hand mechanisms are simultaneously operated by the same two cams 110 and 150.

In the operation of the above described linkages, the supporting arm 90 is first rocked in a clockwise direction viewing Fig. 1 to move the wiping unit from its retracted position to a position in operative relation to the bottle, as shown in Fig. 4, and at the same time the parallel linkage is rocked to present the roller 62 in operative relation to the neck of the bottle at the starting point of the wiping operation with the pivot 84 and roller 62 disposed in a radial plane with relation to the center or axis 72 of the bottle and horizontally spaced therefrom.

During the wiping action the supporting arm 90 remains stationary so that the pivots 104 and 106 are fixed and movement of the inclined roller in a conical path about the tapered neck is effected by operation of the compound linkages with the pivot 84 describing a cylinder having its center corresponding to the center of the bottle and with the roll carrying arm 62 at all times extending in a radial line with respect to the center or axis 72, thus maintaining the roller axis 70 in alignment with the common apex 64 of the cones and presenting the conical surface of the roller in true rolling contact with the label against the conical neck of the bottle.

It will be observed that the proportions of the linkages are such as to effect a circular movement of the roller carrying pivot 84 about the axis of the bottle at a radius x which corresponds to the radius y of the parallel arms 34, 96 about their respective fixed pivots 104, 106 and that the circular or arcuate movement is transmitted in a manner analogous to a pantograph. It will be further observed that the right angle bell crank connections are arranged to maintain the inclined conical wiping roller in a radial plane and always at the same angle to the bottle axis during the wiping operation so that at the completion of the wiping action the pivot 84 and roller 62 are disposed in a substantially vertical radial plane with relation to the center of the bottle as illustrated in Fig. 6. Upon completion of the wiping operation the supporting arm 90 is again rocked, in a counterclockwise direction, to retract the unit to the position shown in Fig. 1 whereupon the bottles are intermittently advanced one station of operation.

The above described operation at station 58 effects wiping of the extended end 100 of the label, and, upon advancement to station 60 the remaining extended end 102 of the label is wiped into overlapping relation to the end 100 by the

right hand mechanism in a similar manner. During the wiping operation at both stations 58, 60, the opposite side of the label, comprising the previously secured connecting portion, is firmly held in place against the neck of the bottle by similar retaining units 156, 158 each being provided with spaced longitudinal yieldable strips 160, 162 shaped to conform to the tapered neck of the bottle. As shown in Fig. 1, the yieldable strips 160, 162 are secured in a holder carried by a reciprocatory slide bar 164 operated in timed relation to the wiping units. After passing station 60 the overlapping portions 100, 102 of the completely applied label are given a final pressing operation by a yieldable pad 166 carried by a reciprocatory bar 168 whereupon the bottle is discharged from the machine by the conveyor 10.

While the preferred embodiment of the invention has been herein illustrated and described, it will be understood that the invention may be embodied in other forms within the scope of the following claims.

Having thus described the invention, what is claimed is:

1. In a labeling machine of the character described, means for supporting an article having a conical surface to be labeled, and means for wiping a label about said conical surface including a conical roller having its apex in common with the apex of the cone of said conical surface, and means for moving said roller in wiping engagement with and around said conical surface.
2. In a labeling machine of the character described, means for supporting an article having a conical surface to be labeled, and means for wiping a label about said conical surface including a roller shaped as a frustum of a cone mounted in an inclined position tangent to the conical surface of the article, and means for moving said roller in an arcuate path about said article while maintaining the roller in said inclined position and in wiping engagement with said conical surface.
3. In a labeling machine, in combination, means for supporting a bottle having a tapered neck forming a frustum of a cone and with a label attached to a portion of said conical surface of the neck with the ends of the label extended, and means for wiping the extended ends of the label about the remaining portion of the conical surface, said means comprising a conical roller having its apex in common with the apex of the cone formed by said tapered neck, and means for mounting and moving said roller through a conical path swung from said fixed apex and in wiping engagement with said tapered neck.
4. In a labeling machine, in combination, means for supporting a bottle having a tapered neck forming a frustum of a cone and with a label attached to a portion of said conical surface of the neck with the ends of the label extended, and means for wiping the extended ends of the label about the remaining portion of the conical surface said means comprising a roller shaped as a frustum of a cone mounted in an inclined position with relation to the vertical axis of the bottle and tangent to the conical surface of the tapered neck, and means for moving said roller in an arcuate path about said bottle while maintaining the roller in said inclined position and in wiping engagement with said conical surface.
5. In a labeling machine, in combination,

means for supporting and intermittently conveying tapered neck bottles in definite spaced relation through successive operation stations of the machine, means for attaching a label to a portion of the conical neck surfaces of successive bottles with the ends of the labels extending substantially parallel to each other, wiping means disposed at one station of operation for wiping one of said extended ends about said conical surface, and wiping means disposed at a succeeding station of operation for wiping the remaining extended end about the remainder of the conical neck, said wiping means being arranged for left hand and right hand operation respectively.

6. In a labeling machine, in combination, means for supporting and intermittently moving a tapered neck bottle having a label attached to a portion of the conical surface of the neck with the ends of the label extending substantially parallel to each other and at a tangent to said conical surface, wiping means disposed at one station of operation for wiping one of said extended ends about said conical surface, and wiping means disposed at a succeeding station of operation for wiping the remaining extended end about the remainder of the conical surface and in overlapping relation to said first end, each of said wiping means including a conical roller having its apex in common with the apex of a cone of said conical surface, and means for moving said roller through a conical path swung from said apex and in wiping engagement with said conical surface.

7. In a labeling machine of the character described, means for supporting an article having a conical surface to be labeled, and means for wiping a label about said conical surface including a roller having the shape of a frustum of a cone with its apex in common with the fixed apex of a cone formed by said conical surface, and means for moving said roller through a conical path swung from said fixed apex and in wiping engagement with said conical surface, said last named means including means for mounting said roller in an inclined position tangent to the conical surface of the article, a pantograph linkage arranged to move said roller mounting through an arcuate path about said article, and parallel linkage interconnected with said pantograph for maintaining said inclined roller in a radial plane and always at the same angle to the bottle axis whereby to effect a rolling contact between the roller and said conical surface.

8. In a labeling machine, in combination, means for supporting and intermittently moving a tapered neck bottle having a label attached to a portion of the conical surface of the neck with the ends of the label extending substantially parallel to each other and at a tangent to said conical surface, wiping means disposed at one station of operation for wiping one of said extended ends about said conical surface, and wiping means disposed at a succeeding station of operation for wiping the remaining extended end about the remainder of the conical surface and in overlapping relation to said first end, each of said wiping means including a roller shaped as the frustum of a cone and means for mounting said roller in an inclined position tangent to the conical surface of the tapered neck bottle, a cam operated pantograph linkage arranged to move said roller mounting through an arcuate path about said neck, and parallel linkage interconnected with said pantograph for maintaining said inclined roller in a radial plane and always at the same angle with respect to the axis of the bottle

whereby to effect a rolling contact with relation to said tapered neck.

9. In a labeling machine, in combination, means for supporting and intermittently moving a tapered neck bottle having a label attached to a portion of the conical surface of the neck with the ends of the label extending substantially parallel to each other and at a tangent to said conical surface, wiping means disposed at one station of operation for wiping one of said extended ends about said conical surface, and wiping means disposed at a succeeding station of operation for wiping the remaining extended end about the remainder of the conical surface and in overlapping relation to said first end, each of said wiping means including a roller shaped as the frustum of a cone and means for mounting said roller in an inclined position tangent to the conical surface of the tapered neck bottle, a cam operated pantograph linkage arranged to move said roller mounting through an arcuate path about said neck, and parallel linkage interconnected with said pantograph for maintaining said inclined roller in a radial plane and always at the same angle with respect to the axis of the bottle whereby to effect a rolling contact with relation to said tapered neck, and cam operated means including a rockingly mounted supporting arm for moving said wiping means into and out of operative relation to said bottle.

10. In a labeling machine, in combination, means for supporting and intermittently moving a tapered neck bottle having a label attached to a portion of the conical surface of the neck with the ends of the label extending substantially parallel to each other and at a tangent to said conical surface, wiping means disposed at one station of operation for wiping one of said extended ends about said conical surface, and wiping means disposed at a succeeding station of operation for wiping the remaining extended end about the remainder of the conical surface and in overlapping relation to said first end, each of said wiping means including a roller shaped as the frustum of a cone and means for mounting said roller in an inclined position tangent to the conical surface of the tapered neck bottle, a cam operated pantograph linkage arranged to move said roller mounting through an arcuate path about said neck, and parallel linkage interconnected with said pantograph for maintaining said inclined roller in a radial plane and always at the same angle with respect to the axis of the bottle whereby to effect a rolling contact with relation to said tapered neck, and cam operated means including a rockingly mounted supporting arm for moving said wiping means into and out of operative relation to said bottle, and operating connections for simultaneously actuating both of said wiping means at said different stations of operation.

11. In a labeling machine, in combination, means for supporting and intermittently moving a bottle having a tapered neck, and means for applying a relatively narrow and arcuate label about the conical surface of said tapered neck comprising means for applying a coating of adhesive to one side of said conical surface, means for attaching a label to said adhesive coated surface with the ends of the label extended laterally, means for applying adhesive to said laterally extended ends, means for pressing the label around one side of the conical surface to dispose the extended ends substantially parallel and at a tangent to said conical surface, wiping

means disposed at one station of operation for wiping one of said extended ends about a portion of the remainder of the conical surface, similar wiping means disposed at a succeeding station of operation for wiping the other extended end about the remainder of the conical surface and in overlapping relation to said first end, and means for pressing the wiped ends of the label in firm engagement with the tapered neck.

12. In a labeling machine, in combination, means for supporting and intermittently moving a bottle having a tapered neck, and means for applying a relatively narrow and arcuate label about the conical surface of said tapered neck comprising means for applying a coating of adhesive to one side of said conical surface, means for attaching a label to said adhesive coated surface with the ends of the label extended laterally, means for applying adhesive to said laterally extended ends, means for pressing the label around said one side of the conical surface to dispose the extended ends substantially parallel and at a tangent to said conical surface, wiping means disposed at one station of operation for wiping one of said extended ends about a portion of the remainder of the conical surface, similar wiping means disposed at a succeeding station of operation for wiping the other extended end about the remainder of the conical surface and in overlapping relation to said first end, and means for pressing the wiped ends of the label in firm engagement with the tapered neck, each of said wiping means including a conical roller having its apex in common with the fixed apex of said conical surface, and means for moving said roller through a conical path swung from said fixed apex and in wiping engagement with said conical surface.

13. The combination with a labeling machine having provision for attaching a label around one

side of the conical surface of a tapered neck bottle with the ends of the label extended, of means for wiping the extended ends about the remaining portion of the conical surface including a conical roller mounted in an inclined position with relation to the axis of the bottle and tangent to the conical surface of the tapered neck, and means for moving said roller through an arcuate path about said bottle while maintaining the roller in said inclined position and in wiping engagement with said conical surface.

14. In a labeling machine of the character described, means for supporting an article having a conical surface to be labeled, means for wiping a label about said conical surface including a frusto-conical roller arranged so that the projection of a line through its axis intersects the projection of a line through the axis of said conical surface, and means for moving said roller in wiping engagement with and around said conical surface.

15. In a labeling machine of the character described, means for supporting an article having a conical surface to be labeled, means for wiping a label about said conical surface including a frusto-conical roller arranged so that the projection of a line through its axis intersects the projection of a line through the axis of said conical surface, and means for effecting relative rotary movement of said conical surface and roller.
